INTERNAL COMBUSTION ENGINE

John Sapp, Republic, Pa.

Application May 13, 1935, Serial No. 21,287

3 Claims. (Cl. 123—14)

This invention relates to internal combustion engines and has for an object to provide an improved rotary combustion engine in which the rotor is provided with cam surfaces which cooperate with spring pressed abutments to form air compression chambers which supply air to automatically open the fuel valve and supply the proper mixture of fuel and compressed air to the compression chamber in which the combustible charge is fired at a point in the cycle of the motor.

A further object is to provide a rotary engine in which the fuel valve will be opened against the tension of its spring by compressed air in a reservoir disposed outwardly from the valve, opening of the valve admitting fuel and air to the chamber in which the charge is fired.

A further object is to provide a rotary engine in which the abutments and the stator will be formed with fingers adapted to interdigitate when the abutments are pressed back into their pockets in the rotor and provide smooth passages of the packing bars past the abutments.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a longitudinal sectional view of an internal combustion engine constructed in accordance with the invention.

Figure 2 is a cross sectional view taken on the line 2—2 of Figure 1.

Figure 3 is a detail sectional view taken on the line 3—3 of Figure 2.

Figure 4 is a detail sectional view taken on the line 4—4 of Figure 5 and showing the packing bars and packing rings, parts being shown in elevation.

Figure 5 is a cross sectional view taken on the line 5—5 of Figure 4.

Figure 6 is a detail perspective view showing the fingers of the stator.

Figure 7 is a diagrammatic view showing both engines spaced apart on the shaft and showing the passages leading to both engines as pipes, also showing the relationship of the air compressor and its pipes, and the fuel pump and its pipes to each other and to both engines.

Figure 8 is a detail perspective view showing

the interdigitating teeth of the stator and abutments.

Briefly the engine comprises two companion engines including respective stators and rotors, the latter being fixed to a common shaft. At 5 diametrically opposite points in the engines respective fuel admission valves admit fuel to compression chambers in succession, for firing. The explosion takes place four times a revolution, and both engines fire simultaneously at points 10 180 degrees apart. Each rotor has four compression chambers and three of the chambers in one rotor and one of the chambers in the other rotor supply highly compressed air simultaneously to the chamber in which the explosion is to 15 occur. Air pipes connect the air inlet ports of the chambers in parallel and air is initially supplied to the pipes by an air compressor such as a blower. The air compressed in the chambers is directed to the chamber in which the charge 20 is to be fired. The initial compression chamber of each motor compresses air to be delivered to the firing chamber of the opposite motor. The other compression chambers of the motor are connected in parallel and supply compressed air 25 for the firing chamber of the motor.

In the various views the two engines are shown as duplicates of each other and hence corresponding parts of both engines are given identical reference numerals to avoid confusion.

Referring to the drawings, 10 designates the stator and 11 the rotor of each engine. The stator includes a cylindrical wall 12 and parallel side walls 13, all of which walls are provided with water jackets 14 through which water may be 35 circulated in any suitable manner.

The rotor 11 is arranged in concentric relation to the stator and includes a hub 15, a relatively heavy annular rim 16, and a web 17 connecting the rim and the hub. The hub has 40 keyed thereto, as shown at 18, a shaft 19 which is journaled in bearings 20 carried by the side walls of the stator.

Referring now to Figures 1 and 7 it will be seen that the rotor is equipped on its periphery 45 with eccentric cam surfaces 21, which terminate in stepped end walls 22 and coact with the inner surface of the stator in forming a plurality of tapered compression chambers. Disposed radially in the stator are spring pressed abutments 50 23, 24, 25 and 26, arranged at a quadrant advance from each other, which enter the compression chamber and bear upon the eccentric surfaces 21 thereof. Inlet ports 27, 28 and 29 are formed in the stator in rear of the respec- 55

tive abutments 23, 24 and 25, and through these ports compressed air is supplied to the chambers. An air compressor, such as a blower, and pipes 31, 32, 33 and 34 are utilized for this purpose. The outlet ports 35, 36 and 37 of the chambers are arranged on the front sides of the abutments. By front is meant in a direction measured in the direction of rotation of the rotor.

10 By referring to Figures 3 and 7 it will be seen that channels 38 are formed in the stators of both motors and these channels deliver compressed air from the initial compression chamber A direct to the air reservoir 39 in the stator of the opposite motor, the reservoir being located in a suitable housing 52. Compressed air from the chambers B and C is delivered directly to the reservoir 39 in the same motor in which they are located, through the medium of channels 37, which connect these 15 chambers in parallel. All of the channels are provided with check valves 40.

The compressed air in the reservoir 39 automatically opens the fuel valve 40 and supplies compressed air for the combustible charge. The 25 fuel valve 40 seals a port 41 through which fuel is supplied under pressure from a pump 42 connected to the port by a pipe 43. The valve also seals a port 44 which communicates with the reservoir 39. A helical compression spring 45 is 30 mounted on the stem of the valve and is held in place by a plug 46. The spring holds the valve closed until sufficient pressure is built up in the reservoir to overcome the tension of the spring and permit the valve to open.

35 After the combustible charge is supplied to the particular chamber in position to be fired, the charge is ignited through the medium of a spark plug 47 or may be fired by the high temperature generated by the compression of the air as in a 40 Diesel engine. During the explosion or power impulses, which take place in both engines at the same moment, the valves 40 are held closed since the pressure of the burning gases is greater than the air pressure in the reservoir and this excess 45 pressure holds the valve closed.

During expansion of the gases the rotor is advanced and the gases exhaust through a port 48. The exhaust port 48 for spent gases is located in front of the abutment 23 of the initial compression 50 chamber A.

The abutments 23, 24 and 25 are mounted in 55 housings 49 carried by the stator and are spring pressed inwardly against the rotor by helical compression springs 50 confined under tension between the outer ends of the abutments and the inner walls of their housings. The abutment 26 however is not mounted in an individual housing but is slidably fitted on the face of an abutment 51 which is mounted in a housing 52 carried by the 60 stator, and a second abutment 53 is mounted in the same housing, and both of the abutments 51 and 53 are spring pressed inwardly by helical compression springs 54 confined under tension between the outer ends of the abutments and the 65 inner wall of the housing 52. The abutments 51 and 53 are independent of each other and tend to prevent loss of compression from the combustible chamber since one of these abutments is in contact with the rotor surface while the other is 70 descending the rotor steps.

The abutment 26 is urged radially by a helical compression spring 55 which is confined under tension between the outer end of the abutment and a lug 56 formed on the abutment 51. The 75 abutment 26 performs the same function as the

abutments 24 and 25, that is, it prevents leakage of the air being compressed in the respective chamber. The two abutments 51 and 53 define a rigid wall of the combustion chamber.

As best shown in Figures 2 and 6 the compression abutments 24, 25 and 26 are provided at their inner ends with forwardly extending tapered fingers 55' as best shown in Figures 2 and 8. The compression abutments 24, 25 and 26 are provided at the inner end with forwardly extending 10 tapered fingers 55' which are set at an oblique angle to the face of the abutment. These fingers interdigitate with similarly constructed fingers 56 carried by the inner surface of the stator. When the abutments are pressed back against the tension of their controlling springs by the cam surfaces of the stator, the interdigitating fingers on the abutments promote smooth passage of the packing bar 60 hereinafter described.

The fingers being disposed diagonally as shown 20 in Figure 2, promote uniform wear on the packing bars instead of forming grooves in the packing bars as would be the case were the fingers disposed parallel with the rim of the rotor, to prevent leak- 25 age between the sides of the stator and the rotor packing rings 57 of the general shape shown in Figure 5 are employed. These rings are housed in seats 58 in the rotor and spring pressed outwardly against the stator by springs 59 disposed in the seats behind the rings. To prevent leak- 30 age between the inner surface of the stator and the peripheral surface of the rotor bars 60 are provided, best shown in Figure 4, these bars being loosely fitted in transverse seats 61 formed in the rotor. Preferably a pair of bars are mounted in 35 each seat and spring pressed apart through the medium of a helical compression spring 62.

In operation there are four impulses during each revolution of each motor. The explosions take place in the compression chambers in suc- 40 cession. One of the four chambers is always firing while the three other chambers are compressing air. Two of the three chambers are delivering air in parallel to the reservoir of the respective motor while the other one of the three 45 chambers is delivering compressed air to the reservoir of the opposite motor. The combustible charges are fired by the spark plug 47 simultaneously to rotate the rotors in, the direction of the arrow. Burnt gases from an explosion are 50 simultaneously exhausted through the exhaust ports 48 while air is being compressed by the remaining compartments for delivery into the reservoirs, the valves of which are held closed by the pressure of the fired mixture.

The reason why the initial compression chamber of each motor delivers its supply into the reservoir of the other motor is that the outlet channel 38 of the compression chamber is directly opposite the reservoir 39 of the opposite 60 motor.

From the above description it is thought that the construction and operation of the invention will be fully understood without further explana- 65 tion.

What is claimed is:

1. In a rotary internal combustion engine, a stator forming a cylindrical enclosure, a shaft rotatably and concentrically mounted within said stator, a rotor fixed on said shaft, said rotor having uniformly spaced cam surfaces providing with the cylindrical wall of said stator a corresponding number of arcuate tapered compression and explosion chambers, uniformly spaced abutments carried by said stator, each abutment be- 70 75 75

ing slideable radially of said stator and spring pressed into sliding engagement with said rotor, there being an air inlet port immediately in rear of each abutment, a fuel port in the stator supplying combustible mixture to the chambers in succession, a reservoir in the stator having a passage communicating with the fuel port, a spring pressed valve closing the passage, means connecting the air inlet ports in parallel to a source of compressed air, there being openings in said stator immediately in front of each abutment, one of said openings being disposed next forwardly of said fuel port and being an exhaust opening, and means connecting the remaining ones of the last named openings in parallel to said reservoir.

2. In a rotary internal combustion engine, a stator forming a cylindrical enclosure, a shaft rotatably and concentrically mounted within the stator, rotors fixedly mounted on said shaft, each rotor having uniformly spaced cam surfaces providing with the cylindrical wall of said stator a corresponding number of arcuate tapered compression and explosion chambers uniformly spaced apart, abutments carried by said stator uniformly spaced apart, each abutment being slideable radially of said stator and spring pressed into sliding engagement with a respective rotor, there being an air inlet port in the stator immediately in rear of each abutment, a fuel port in the stator for supplying a combustible mixture to the chambers of a respective rotor in succession, a fuel reservoir in the stator for each rotor having a passage communicating with the fuel

port, a spring pressed valve controlling the passage, means connecting the air inlet ports in parallel to a source of compressed air, there being openings in said stator immediately in front of each abutment, one of said openings next forwardly of said fuel port being an exhaust opening, the other ones of said openings being compressed air openings, means connecting the initial one of said compressed air openings next forwardly of the exhaust opening for a respective rotor to the fuel reservoir of the opposite rotor, and means connecting the remaining ones of said openings in parallel to the reservoir of the respective rotor.

3. In a rotary internal combustion engine, a stator, a plurality of radially extending spring pressed abutments carried by the stator, a rotor having a plurality of spaced arcuate tapered chambers having externally disposed curved walls formed in the periphery receiving said abutments, means for admitting and firing a charge in one of the chambers, compression passages connecting one end of each of the other chambers with said means, means for connecting said passages to a source of compressed air, packing bars on the periphery of the rotor, spaced fingers carried by the abutments and arranged to engage the inner face of the stator, and spaced fingers carried by the stator adapted to interdigitate with the abutment fingers for promoting smooth passing of the packing bars past the abutment.

JOHN SAPP.
